MOSES G. HUBBARD, OF CHATHAM, NEW JERSEY, ASSIGNOR TO MECHANICAL UTILITIES COMPANY, OF NEW YORK, N. Y., A CORPORATION OF NEW YORK.

CENTRIFUGAL FAN OR PUMP.

No. 902,583.

Specification of Letters Patent.

Patented Oct. 27, 1908.

Application filed May 29, 1908. Serial No. 435,761.

To all whom it may concern:

Be it known that I, MOSES G. HUBBARD, a citizen of the United States, residing at Chatham, county of Morris, and State of New Jersey, have invented certain new and useful Improvements in Centrifugal Fans or Pumps, of which the following is a specification.

This invention relates to that class of centrifugal fans or pumps, in which the fluid 10 acted upon is taken in axially and discharged circumferentially. In this type of centrifugal fan or pump the rotary member is usually formed with a large number of parallel thin blades arranged in drum form. In constructing the rotary member in this type of fan, the blades have in the past usually been made of separate pieces suitably attached to the heads or other parts of a rotating frame, which construction is objectionable on account 15 of the relatively large cost of manufacture, and because of the limitations to the number of blades that can be effectively mounted within a given circumference. It has also been suggested that the blades be 20 formed by stamping or punching out sheet metal, but, so far as I am aware, no practical or economical method of carrying out this plan has yet been developed which obviates the stated limitations as to the number and 25 size of blades that can be mounted in a given circumference.

The object of my present invention is to simplify and improve the construction of the rotary member of this type of centrifugal fan 30 or pump, with a view to reducing the cost of manufacture and increasing its efficiency. To this end I propose to construct an adjustably connected series of blades for the rotary member of a centrifugal fan or pump, by 35 means which will permit the mounting of a relatively larger number of blades in a rotary member of a given circumference.

My invention comprises a series of blades or leaves connected at their ends with uniting 40 strips which are capable of being bent or crimped transversely into zigzag or corrugated form to present the blades in proper relation, the entire series being then formed into the proper shape and suitably mounted 45 between heads constituting the frame by which the rotary member is secured upon its supporting shaft. In the preferred method 50 of constructing my improved centrifugal fan or pump, I take a strip of sheet metal of 55 proper length and width, and by a cutting or

stamping operation, form in the strip the desired number of internal blades or leaves, all of which are connected at their ends to the body of the strip. These blades or leaves are then bent with relation to the body of the strip to place them at the desired angle, and to give them the required concave or other shape, and the portions of the strip, from which parts of the ends of the blades or leaves have been severed, are then crimped 65 or bent transversely to present the succession of blades or leaves in the desired close relation. The integrally connected series of blades or leaves formed in this way is then shaped into drum form and fastened between 70 the heads of the rotary member by any suitable fastening devices.

My invention can be carried out by forming the blades or leaves separately and riveting them at their ends to the uniting strips 75 before said strips are bent or corrugated to present the blades or leaves in proper relation. I can also carry out my invention by stamping or punching several pieces of sheet metal to form a plurality of segments of 80 blades or leaves which are secured together by riveting the sections of uniting strips or edge walls before corrugating. I prefer, however, to form the blades or leaves and uniting strips from a single integral piece of 85 sheet metal. Without regard to the particular form of the structure for carrying out my invention, it will be understood that the essential feature is the adjustable uniting strip by which the blades or leaves are presented in the desired close relationship, and by which the number of blades or leaves can be greatly increased in a drum of a given circumference.

In order that my invention may be fully 90 understood, I will first describe the same with reference to the accompanying drawings, and afterwards point out the novelty more clearly in the annexed claims.

In said drawings Figure 1 is a vertical 100 transverse sectional view of a rotary fan or blower constructed in accordance with my invention and showing the same applied in a snail shell form of casing. Fig. 2 is a vertical longitudinal sectional view of the same. Fig. 3 is a vertical longitudinal sectional view of my improved fan or pump showing a modified arrangement of casing and mounting. Fig. 4 is a detail front elevation of the 105 form shown in Fig. 3. Fig. 5 is a detail plan 111.

view of part of a blank strip of sheet metal having a number of blades or leaves cut therein. Fig. 6 is a similar view illustrating the blank after it has been crimped or bent 5 into final shape. Fig. 7 is a detail transverse sectional view of part of the rotary member of my improved fan or pump showing the arrangement of the parallel blades or leaves. Fig. 8 is a detail view illustrating a 10 hook bolt for fastening the series of blades between the heads of the rotary member, and Fig. 9 is a detail plan view of a slight modification.

In constructing my improved rotary fan or 15 blower I take a long strip of the proper kind of sheet metal having the required length and width to produce the fan of the desired size, a portion of which strip is illustrated at 1 in Fig. 5 of the drawings, and by any approved cutting or stamping process I form a series of 20 parallel elongated blades or leaves, indicated at 5, 5, 5, &c. These blades or leaves are formed entirely within the edges of the blank 1, their ends being formed partly by the short 25 longitudinal cuts *a*, arranged parallel with the length of the blank strip 1, and partly by the edges of the blank, and their longitudinal edges being formed by the long cuts *b* extending at right angles to the length of the blank 30 strip 1. Each blade or leaf 5 is integrally connected with the edge portion *c* of the body of the blank 1, said edge portion *c* constituting adjustable uniting strips as hereinafter explained.

35 After the blank has been cut in the manner described, the cut blank is subjected to a crimping or bending operation to bend transversely the edge portions or uniting strips *c* of the blank, said uniting strips being bent 40 alternately up and down upon lines extending transversely of the blank substantially coincidently with the ends of the short cuts *a*. This crimping or bending operation effects the transverse corrugation of the uniting strips *c* and renders said uniting strips 45 adjustable in length, since it is possible to increase or decrease the several bends to present the several blades or leaves closer together and farther apart. This crimping or bending operation presents the several 50 blades or leaves in approximately their proper angular relation, although the blades or leaves may also be curved or otherwise shaped. The blank bent in this form is 55 shown in Figs. 6 and 7, from which views it will be observed that the inner and outer edges of each blade or leaf 5 is formed by two adjacent cuts *b* in the blank. It will also be 60 observed from the drawings that the entire surface of the blank strip within the short longitudinal cuts *a* is utilized as blade surface, and that each blade is integrally connected at its opposite ends for a portion of its width with uniting strip portions of the body 65 of the blank.

In Fig. 7 of the drawings, I have shown a modified form of the invention, in which the blades or leaves 5^a are made of separate parts, each being formed with integral lugs or flanges 5^b at its opposite ends, which are 7 riveted or otherwise rigidly secured to the separate adjustable uniting strips *c*. In carrying out the invention in this form, it will of course be understood, that the blades or leaves are secured to the uniting strips the 75 proper distances apart, and the uniting strips are then subjected to the crimping or bending operation to shape and present the several blades or leaves in proper relation.

It will, of course, be understood that the 80 width of the several blades or leaves must be determined upon to suit the requirements of the particular fan or pump that is to be constructed. In the preferred form of the invention, if it should prove desirable to form 85 the blades or leaves narrower than would result from the mere stamping or cutting of the blank as explained, it will, of course, be understood that a portion of the width of each blade or leaf may be cut off. This cutting 90 away of a part of each blade or leaf will ordinarily be unnecessary, since by proper calculation, the width of the blades or leaves can be arranged to meet the proper requirements.

The series of blades formed as just described, are mounted in drum form between two circular heads best shown in Figs. 1 and 2. The main supporting head 10 is formed integral with a conical end 11, which is suitably flanged and mounted upon a hub 12, which is secured in the usual way to a supporting shaft 13. This circular head 10 is preferably formed with an inturned annular flange 10^a, for the purpose of fitting over one 100 of the corrugated uniting strips of the series of blades or leaves. The opposite circular head 15 is formed with inner and outer annular flanges 15^a and 15^b, which fit over the opposite corrugated uniting strip of the series 105 of blades or leaves. When the series of blades or leaves in drum form has been placed between the heads 10 and 15, a suitable number of hook bolts 20, such as shown 110 in detail in Fig. 8, is arranged as shown to 115 engage the uniting strip portions *c* of the series of blades at intervals, and passed through suitable openings in the heads to receive nuts by which the heads and series of blades are rigidly secured together to form 120 the rotary member of the fan or pump. It will, of course, be understood that any suitable means may be employed for mounting the series of blades or leaves in the desired 125 adjusted relation within the heads or other rotating frame.

In Fig. 2 I have shown the rotary fan or pump provided with a plurality of propeller like blades 25, which extend approximately 130 radially from the hub 12 to the inner edge of

the head 15. These blades 25 serve to assist the action of the fan or pump by drawing the fluid into the eye of the rotary member. These blades 25 also act as spokes for bracing the circular head 15 upon the hub 12, thereby producing a more rigid structure for the rotary member.

My improved rotary fan or pump may be mounted in any suitable form of casing. In Figs. 1 and 2 I have shown it mounted in the ordinary snail shell casing, in which the fluid is drawn in through the axial opening 30, and expelled by centrifugal force through the rotary member into the snail shell casing 31, from which it is forced through the outlet 32. In this adaptation of my invention, the shaft 13 of the rotary member may be suitably journaled at 35 in the standard 36, and supplied with a driving pulley 37, although the fan may be driven in any approved manner.

In Figs. 3 and 4 I have shown my improved centrifugal fan or pump applied to the form of casing adapted for window ventilation, as shown in my pending application filed No. 25 on December 25th, 1907, Serial No. 403,632. In this adaptation of my invention, 40 represents the casing adapted to be mounted in the window frame, with the screened inlet end 41 leading from the outer air. A centrifugal fan or pump 45 is mounted directly upon the motor shaft 46 of the electric motor 47, hung within the casing by the yoke frame 48. Adjacent to the outlet end of the casing 40, and surrounding the fan or pump 45, is an annular inwardly curved deflected wall 50, having an air inlet 51, through which the air passes to the eye of the fan or pump 45. This deflecting wall serves the double function of directing the incoming air to the eye of the rotary fan or pump, and of deflecting the centrifugally discharged air outwardly into the room to be ventilated.

There are many advantages in my improved construction. The structure is simple and economical in manufacture, and at the same time is strong, durable and efficient. The economy in manufacture is not only due to the facility with which the parts can be made and assembled, but also to the fact that there is no waste of material in constructing the device. Substantially the whole of the surface area of the blank from which the series of blades is made, is utilized as active surface in the rotary fan or pump. With my improved construction it is possible to arrange the blades or leaves of the rotary member as close together or as far apart as may be desired, by bending the intervening uniting strips more or less, so that within a given circumference of the rotary member any desired number of blades or leaves may be arranged, it being simply necessary to start with the required length of blank (or length of uniting strips) and bend the uniting

strips connecting the several blades more or less to suit the dimensions of the pump to be constructed.

As showing the increased efficiency of my improved construction of centrifugal fan or pump, I would call attention, in addition to the facility for effectively increasing the number of blades or leaves in a rotary member of a given circumference, to the fact that in forming the blades or leaves as above described, I am able to obtain the sharp cutting edge at the outer edge of each blade or leaf, a feature of great importance in connection with the efficiency of a fan or pump of this type.

What I claim is:

1. In a fan or pump, the combination of a plurality of blades or leaves, with a uniting strip connected with all of said blades or leaves and bent between its connections with said blades or leaves to determine the relative position of said blades or leaves.

2. A centrifugal fan or pump having a rotary member comprising a plurality of blades or leaves connected with a uniting strip, which is bent alternately up and down in a zigzag form, as set forth.

3. A centrifugal fan or pump having a rotary member comprising a suitable frame, a plurality of blades or leaves, corrugated uniting strips connecting said blades or leaves, and means for securing said connected blades or leaves within said frame.

4. A centrifugal fan or pump having a rotary member comprising a sheet of metal, having a series of transverse parallel cuts between its edges and bent to form a series of substantially parallel blades whose upper and lower edges are defined by said transverse cuts.

5. A centrifugal fan or pump having a rotary member comprising a sheet of metal having a series of transverse parallel cuts between its edges and two series of longitudinal cuts parallel with its edges, said sheet of metal being bent to form a series of substantially parallel blades whose upper and lower edges are defined by adjacent transverse cuts.

6. A centrifugal fan or pump having a rotary member comprising a sheet of metal stamped or cut to form a plurality of blades or leaves wholly within its edges, and uniting strips or end walls, said blades or leaves having stamped or cut upper and lower edges, and said end walls being bent to present said blades or leaves in proper relation.

7. A centrifugal fan or pump having a rotary member comprising a sheet of metal stamped or cut to form a plurality of blades or leaves wholly within its edges, and uniting strips or end walls corrugated to present said blades or leaves in proper relation, said connected series of blades or leaves being shaped into drum form, as set forth.

8. A centrifugal fan or pump having a rotary member comprising a sheet of metal stamped or cut to form a plurality of blades or leaves wholly within its edges, uniting strips or end walls corrugated to present said blades or leaves in proper relation, said connected series of blades or leaves being shaped into drum form, and heads secured to said drum of blades or leaves, as set forth.
10. 9. In a centrifugal fan or pump, a strip of metal cut to form a plurality of blades or leaves and bent in drum form, in combination with heads fitting upon the opposite ends of said drum of blades or leaves, and means for securing said heads in position thereon.
10. In a centrifugal fan or pump, a blank cut to form a plurality of internal blades or leaves and crimped or bent along its edge walls, in combination with heads, and hook bolts for securing said blank in drum form between said heads.
11. A centrifugal fan or pump, having a rotary member comprising a plurality of blades or leaves in drum form connected at their ends with zigzag or corrugated uniting strips, heads fitting over said corrugated uniting strips, and hook-bolts engaging said uniting strips and passing through said heads, as set forth.
12. A centrifugal fan or pump, having a rotary member comprising a plurality of blades or leaves in drum form connected at

their ends with zigzag or corrugated uniting strips, annularly flanged heads fitting over said corrugated uniting strips, and means for securing said heads thereon, as set forth.

13. A centrifugal fan or pump, having a rotary member comprising a plurality of blades or leaves in drum form connected at their ends with zigzag or corrugated uniting strips, and flanged heads secured to the ends of the drum of blades or leaves, a hub secured to one of said heads, and a shaft upon which said hub is mounted, as set forth.

14. A centrifugal fan or pump having a rotary member comprising a plurality of blades or leaves in drum form connected at their ends with zigzag or corrugated uniting strips, flanged heads secured to the ends of the drum of blades or leaves, a hub secured to one of said heads, and a series of propeller like blades extending between said hub and said other head, as set forth.

15. In a centrifugal fan or pump, the combination of a suitable casing, with a rotary member comprising a plurality of blades or leaves in drum form connected at their ends with zigzag or corrugated uniting strips, and a frame upon which said drum of blades or leaves is mounted, and a shaft supporting said frame, as set forth.

MOSES G. HUBBARD.
